UNITED STATES PATENT OFFICE.

BONNIE L. MALLORY, OF CLEVELAND, OHIO.

JOINT FOR LONGITUDINAL MEMBERS.

1,111,480.

Specification of Letters Patent.

Patented Sept. 22, 1914.

Application filed December 29, 1911. Serial No. 668,570.

To all whom it may concern:

Be it known that I, BONNIE L. MALLORY, a citizen of the United States, residing at Cleveland, in the county of Cuyahoga and State of Ohio, have invented a new and useful Improvement in Joints for Longitudinal Members, of which the following is a full, clear, and exact description, reference being had to the accompanying drawings.

This invention relates to joints between the ends of longitudinal members, such as railway rails, I-beams and the like, and, generally speaking, it has for its object the simplification and cheapening of joints of this character without, by so doing, destroying their efficiency. Many of these joints have been devised that would be quite strong and noiseless if they could be produced commercially, but they have been so shaped that the excessive cost of their manufacture has made their use impracticable. In my present form of joint I have retained most of the advantages of these complex forms, and have so designed it that it can be produced with sufficient economy as to make practical its extensive use. Moreover, I have adapted it for use in railway constructions having electric signaling systems, all as will more clearly appear from the following specification describing the joint shown in the accompanying drawings, in which—

Figures 1 and 2 are perspective views of the adjacent ends of a pair of railway rails that have been shaped in the manner for forming my improved joint; Fig. 3 is a plan view, partly in section, showing parts of the rails of the foregoing figures joined; Fig. 4 is a side elevation of the ends of the joined rails; Figs. 5 and 6 are transverse sections taken on lines 5—5 and 6—6, respectively of Fig. 4; Fig. 7 is a sectional view like that of Fig. 6 except that it shows the insulation that may be used in the joint when desired for use in an electric signaling system; Figs. 8 and 9 are perspective views of the prepared pieces of insulation for use in my joint, and Fig. 10 is a perspective view of my joint as applied to an I-beam.

First taking up a description of the railway-rail joint, shown in Figs. 1 to 6, A and B represent the respective adjacent ends of two railway rails, the same having the usual base and wheel flanges and the connecting webs. Projecting longitudinally from the ends of these rails are web members A' and B' respectively. These web members are identically alike, one being formed at each

end of each rail but on opposite sides of the median line of the rail so that, in the completed joint, they form complements of each other, as will hereinafter appear. These members are each provided with base flanges, shown at A² and B², the same being continuations of the base flanges of the rail proper. The upper parts of the wheel flanges of the rails are omitted from the web-extensions for a space adjacent the ends of the rails, as shown at A³ and B³ respectively, beyond which spaces the full thickness of the flanges is again supplied, as shown at A⁴, B⁴. In the assembled joint, the wheel flange sections A⁴ and B⁴ are contained within the spaces B³ and A³ respectively, the parts being held together by bolts C that are passed through holes C' in the webs of the rails and through registering holes C² in lugs A⁵ and B⁵ that project longitudinally from the free ends of the web members A' and B'. The holes C' and C² are slightly elongated, as shown, to provide for possible expansion and contraction of the rails with changes in temperature, while the wheel-flange sections A⁴ and B⁴ are made slightly shorter than their containing spaces for the same purpose. By making the spaces A³—B³ and the flange sections A⁴—B⁴ thinner than the wheel flange proper, a broad and strong base support is provided for said sections.

In order to hold the bolts C from turning while screwing on their nuts, bosses A⁶ and B⁶ are formed on the web members, these bosses having extensions A⁷, B⁷ on opposite sides of the bolt hole C' in position to engage with the sides of the bolt heads. The heads of those bolts that are next the web members are thus confined on three sides as if they were held in a wrench and are thereby prevented from turning. For holding the other bolts C, a lug B⁸ is formed on the web of the rail B to engage with one side of the bolt head, it being understood that a corresponding lug is formed on the rail A.

The wheel flange sections A⁴ and B⁴, as well as the spaces A³ and B³ are provided with beveled or transversely inclined ends, as shown, in order to facilitate assembling the rails and to deaden the noise, it being understood that, with this construction, the wheels will rest on both rails at the same time and will not pass instantly from one rail to the other with the accompanying noise and shock, as is common with the ordinary joint.

In Figs. 8 and 9 I have shown prepared sheets of insulating material, such as fiber, or the like, the same to be used in the joint to separate the rails electrically, as is sometimes necessary in electric signaling systems. The piece shown in Fig. 9 is intended for use under the lugs A⁵ and B⁶ and transversely between the rails at that part of the joint. Thus the part D, with the edge flanges D' and D², insulates the lug B⁵, as appears from Fig. 7, the bolts C passing through the holes D³. For still further insulating the lug, the bolt is surrounded with a spool of bushing D⁴ of fiber or other suitable material. For insulating the joint transversely of the rails, the part D is further provided with a flange D⁵, at each end of which is a flange D⁶, D⁷ respectively, said flanges being so shaped as to fit the end of the rail proper about the web member, as will be clear from a comparison of Fig. 9 with the end of the rail proper in Fig. 1.

The parts E and F, with their attached flanges E' and F', lie between the web members A' and B', the flanges E' and F' being turned over to separate the wheel flange sections B⁴ and A⁴ respectively from the web members A' and B'. Short lips E² and F² are turned up at the adjacent ends of the flanges E' and F' to fill the space between the wheel flange sections A⁴ and B⁴.

In Fig. 10 I have shown my improved joint applied to I-beams. These beams are represented at G and H. The web member H' with its lug H⁵ and top flange section H⁴ correspond in shape and function to the parts B', B⁵ and B⁴ of the rail B shown in Fig. 4, while the top flange section G⁴ corresponds to the wheel flange section A⁴. In the I-beam, the parts are preferably held together by rivets R instead of by bolts, although the latter may be employed.

Having thus described my invention, what I claim as new and desire to secure by Letters Patent is:

1. In a joint for longitudinal members, the combination with said members, of overlapping web members projecting from the adjacent ends of the longitudinal members, and a top flange section projecting from each of the web members over the other web member, each of the web members and its respective top flange section terminating in a common plane that is disposed at an obtuse angle to the longitudinal axis of the first mentioned members, the ends of the longitudinal members being inclined in a plane parallel to the ends of the web members, and a lug which projects from the end of each of the web members, for the purpose specified.

60 2. In a joint for longitudinal members, the combination with said members, of overlapping web members projecting from the adjacent ends of the longitudinal members,

a top flange section projecting from each of the web members over the other web member, each of the web members and its respective top flange section terminating in a common plane that is disposed at an obtuse angle to the longitudinal axis of the first mentioned members, the ends of the longitudinal members being inclined in a plane parallel to the ends of the web members, and a lug which projects from the end of each of the web members, for the purpose specified.

3. In a joint for railway rails, the combination with said rails, each of which is provided with the usual base and wheel flanges and connecting web, of a web member on each rail, said members overlapping and forming, in effect, a continuation of the web of the rails proper, and a wheel flange section on each of the web members which are separated from the rails proper by spaces in which the sections on the opposite rails rest, each of the web members and its respective wheel flange section terminating in a common plane that is disposed at an obtuse angle to the longitudinal axis of the rail, the ends of the rails being inclined transversely in a plane parallel to the ends of the web members, the adjacent ends of the wheel flange sections being inclined at an angle which is substantially the reverse of the angle of inclination of the ends of the rails.

4. In a joint for railway rails, the combination with said rails, each of which is provided with the usual base and wheel flanges and connecting web, of a web member on each rail, said members overlapping and forming, in effect, a continuation of the web of the rails proper, a wheel flange section on each of the web members which are separated from the rails proper by spaces in which the sections on the opposite rails rest, each of the web members and its respective wheel flange section terminating in a common plane that is disposed at an obtuse angle to the longitudinal axis of the rail, the ends of the rails being inclined transversely in a plane parallel to the ends of the web members, the adjacent ends of the wheel and a lug which projects from the end of each of the web members, for the purpose specified.

In testimony whereof, I hereunto affix my signature in the presence of two witnesses.

BONNIE L. MALLORY.
